UNITED STATES PATENT OFFICE

BLANCHE F. MACKENZIE, OF JAMAICA PLAIN, MASSACHUSETTS

SKIRT MARKER

Application filed December 27, 1927. Serial No. 242,542.

This invention relates to devices for making marks on a skirt to serve as guides in turning up the skirt.

The fact that it is a difficult matter for a woman to turn up a skirt and get it even, without assistance, is known only too well both to the gentler sex and also to a substantial part of the opposite sex who have been called upon for more or less expert observation and assistance in this matter. While skirt marking devices have been proposed heretofore and are in use to some extent, they are intended chiefly for tailors and dressmakers rather than for individual use.

15 The present invention aims to devise an apparatus with a woman can without assistance, make the height marks necessary to guide her in turning up a skirt. It is also an object of the invention to provide an apparatus of this character which can be manufactured economically, will be convenient to use, and which can be packed into a small space for shipment or when not in use.

25 The nature of the invention will be readily understood from the following description when read in connection with the accompanying drawings, and the novel features will be particularly pointed out in the appended claim.

30 In the drawings,

Figure 1 is a perspective view showing an apparatus embodying this invention and illustrating a convenient method of using the apparatus;

35 Fig. 2 is a vertical, cross-sectional view through the can or container for the powder which is used in making the marks on the skirt;

40 Fig. 3 is a perspective view showing the spring clamp which preferably is used to support the powder container in its operative position; and

45 Fig. 4 is a plan view of the powder container and clamp fastened to a door, the door being shown in horizontal cross-section.

The apparatus shown comprises a container 2 adapted to hold a quantity of powdered material 3, such as powdered talc, chalk, or the like. This container may conveniently 50 consist of a sheet metal can, and it is pro-

vided at one side with a laterally projecting tapered nozzle 4 through which the powder may be discharged by a blast of air directed against the main body of powder 3 in the can. Preferably the can is provided with a screw top or cover 5 which may be conveniently removed for refilling, and a metal air tube 6 is soldered or otherwise secured in an upright position in this cover 5. A rubber tube 7 is connected to the upper end of the metal tube 6 and connects the container with a bulb 8, Fig. 1, this bulb preferably having the usual check valves so that by squeezing the bulb a puff or jet of air will be propelled through the tubes 7 and 6 into the can 2. 60 This jet of air striking the powder 3 will pick up a small quantity of the powder and expel it through the nozzle 4.

One of the objections to prior forms of skirt markers has been the fact that they require a stand or some relatively bulky support which is objectionable both from a manufacturing standpoint and also because it makes the device somewhat cumbersome. In order to overcome this difficulty I have provided a clamp or attaching device by means of which the container or can 2 can be adjustably fastened to the edge of a door, the leg of a chair, or any other convenient support of a character that is found in any household. Preferably a spring clamp, such as that shown in the drawings, is used. This clamp comprises a U-shaped member 9 made of resilient sheet metal and having legs 10 and 11, the leg 10 being bent backwardly as indicated at 12. Such a clamp may be slipped over the edge of a door or other convenient support, as shown in Figs. 1 and 4, the door being gripped between the parts 11 and 12. Preferably the opposed surfaces of these parts are covered as shown at 13 with leather, or a napped fabric, such as velvet, in order better to grip the door and to avoid marring its surfaces.

The container may be fastened to the clamp 95 in any convenient manner. As shown, it is provided with a clip 14 secured to its rearward surface, this clip being adapted to slip over a part of the clamp, as shown in Fig. 4, to support the container on the clamp. 100

In using the apparatus it is fastened to a door or other convenient support in the manner above described, and the user then stands in such a position that the surface of the skirt 5 is spaced slightly from the discharge end of the nozzle 4. The container should be adjusted so that the end of the nozzle is at the proper distance from the floor. By squeezing the bulb 8 slightly a small quantity of 10 powder is ejected from the nozzle, as above described, thus making a small round spot on the outer surface of the skirt. The user then turns slightly and squeezes the bulb again so as to make another spot a short distance 15 from the first one. These operations are repeated until a row of spots or marks has been made entirely around the skirt. If the user stands erect on both feet in the proper position, all of the marks will be at the same 20 height above the floor. It is then a simple matter to turn up the skirt.

The device thus enables a woman to mark a skirt accurately and quickly without assistance from others. It will be observed that 25 the device is very simple in construction, can be manufactured economically, and that the ease with which it can be placed in position for the marking operation, or removed from such position, makes it very convenient to use. 30 The apparatus is so organized that it can be easily packed and shipped, and when not in use it occupies very little space in a work basket, or the like.

While I have herein shown and described 35 a preferred embodiment of my invention, it will be understood that the invention may be embodied in other forms without departing from the spirit or scope thereof.

Having thus described my invention, what 40 I desire to claim as new is:

A skirt marker comprising an upright container adapted to hold a quantity of powder and having a discharge nozzle projecting laterally from the upper part thereof, a tube 45 projecting downwardly into the container for a substantial distance below said nozzle, a flexible tube connected with the first mentioned tube, a bulb connected with said flexible tube for forcing air through both of said 50 tubes and against the powder in said container whereby a part of the powder will be lifted by the blast of air and ejected through said nozzle, a U-shaped spring clamp having legs adapted to straddle the edge of the door 55 and one of said legs being bent backwardly upon itself to cooperate with the opposite leg to grip the edge portions of doors varying substantially in width, and a clip carried by 60 said container and adapted to be slipped over a part of said clamp to support the container on the clamp.

BLANCHE F. MACKENZIE.
